(57) **CLAIM**

The ornamental design for truck quarter fenders, as shown and described.

DESCRIPTION

FIG. 1 is a rear perspective view of a truck quarter fender showing a first embodiment of our new design;

FIG. 2 is a top plan view of the truck quarter fender of FIG. 1;

FIG. 3 is a bottom plan view of the truck quarter fender of FIG. 1;

FIG. 4 is a front elevational view of the truck quarter fender of FIG. 1;

FIG. 5 is a rear elevational view of the truck quarter fender of FIG. 1;

FIG. 6 is a left side elevational view of the truck quarter fender of FIG. 1;

FIG. 7 is a right side elevational view of the truck quarter fender of FIG. 1;

FIG. 8 is a front perspective view of a truck quarter fender showing a second embodiment of our new design;

FIG. 9 is a top plan view of the truck quarter fender of FIG. 8;

FIG. 10 is a bottom plan view of the truck quarter fender of FIG. 8;

FIG. 11 is a front elevational view of the truck quarter fender of FIG. 8;

FIG. 12 is a rear elevational view of the truck quarter fender of FIG. 8;

FIG. 13 is a left side elevational view of the truck quarter fender of FIG. 8; and,

FIG. 14 is a right side elevational view of the truck quarter fender of FIG. 8.

The broken lines in the drawings form no part of the claimed design.
